UNITED STATES PATENT OFFICE

2,447,173

AIR CHARGER

Leonard E. Gordon, Oakland, Calif.

Application December 21, 1945, Serial No. 636,397

11 Claims. (Cl. 222—484)

1

This invention relates to devices for introducing into closed containers, such as liquid storage tanks, quantities of air sufficient to provide an air cushion above the level of water in the tank.

An object of the invention is to provide, in apparatus of the character described, novel mechanism which is motivated by the flow of liquid from the container for injecting air into the container against the resistance of fluid under pressure which is already present in the container.

Still another object of the invention is to provide in a water storage tank, provided with a side inlet for admitting air, means operative to force air into the tank through said inlet even though the water in the tank covers or extends above the level of the inlet.

A further object of the invention is to provide a mechanical air charger which is not liable to become fouled or clogged by the presence of sediment in the liquid.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to the drawing:

Figure 1 is a view partly in side elevation and partly in vertical section showing one form of the air charger of my invention connected with a storage tank.

Figure 2 is a vertical sectional view of the charger motor showing the plunger thereof in the position it occupies while liquid is being withdrawn from the container.

Figure 3 is a side elevational view, partly in vertical section, of one form of liquid-actuated piston.

Figure 4 is a partial vertical sectional view of a modified form of charger motor.

The apparatus of my invention is particularly adapted for use in domestic water supply systems in which pressure is supplied and maintained by means of a power-driven pump or the like in order to maintain the constant pressure desired at various service outlets so as to insure an adequate volume of flow at all times regardless of whether or not the pump may be operating. In many localities, especially in outlying districts

2

not served by the constant pressure mains of a public utility company, water for drinking purposes and other uses is drawn from still water sources such as remotely situated springs or wells, the aforesaid power-driven pumps being employed for conveying the water to the house service mains and for elevating the pressure in the mains to produce the aforementioned sufficiency of flow when one or more faucets or other outlets are opened in the system. Due to the fact that the frequency of water withdrawals and the quantity of water required at each withdrawal may vary widely from time to time, sometimes hours elapsing between demands, it would be obviously impractical to keep the pump running continuously to maintain the line pressure since this would cause undue wear in the pump and motor and unnecessary waste of power. It is common practice in such water supply systems to provide a storage tank or accumulator intermediate the pump and the house mains capable of holding under pressure a considerable quantity of previously pumped water which may be periodically replenished by the pump as a predetermined quantity of water is withdrawn from the tank.

In such a tank, a volume of air is maintained at the top thereof above the water which serves as a compressible cushion yieldable as the water level rises and falls between high and low positions in the tank and at which positions, respectively, the water supply pump may stop and start in response to the operations of a control switch actuated by present high and low pressures of said air cushion. This air cushion besides serving, when compressed, to effect ejection of water from the tank has a bearing on the frequency of pump operation since, if a comparatively large volume of air is present in the tank, a correspondingly large volume of water will flow from the tank between stops and starts of the pump. Due to minute leaks in the tank or to progressive absorption of the air by the water due to the air molecules being held between water molecules, much in the same manner that carbonic acid gas is absorbed in the manufacture of charged water, the air cushion will, in time, completely disappear resulting in so-called "waterlogging" and actuation of the pump control switch each time that a faucet or other outlet is opened in the service line. It is thus apparent that replenishment of the air lost as explained above is imperative in order to maintain proper operation of the water supply

system and to minimize possible overworking of and damage to the pumping unit and its controls.

In the drawing, I have shown a tank 6 of any desired size and which is of the closed type familiarly employed in service systems of the character mentioned above. Since these tanks are common and familiar to those skilled in the art, the water charging portions of the system are omitted since they form no part of nor modify the present invention. Extending from the tank 6 a few inches above the bottom of the latter is a water outlet nipple 7 to which is threadedly engaged the upper boss 8 of the air charger housing 9 which is also provided with a lower boss 11 preferably diametrically opposed to the boss 8 and situated several inches below the horizontal plane of the latter. The boss 11 may be threadedly engaged with a dispensing faucet 10 as shown, or the latter may be replaced by a suitable service conduit. Both bosses 8 and 11 are provided with axial passages 12 and 13 respectively, which are in communication with a cylinder bore 14 formed axially of the housing and having an abutment 16 marking its lower end. The housing is also provided with a well 17 forming an axial extension of the lower end of the cylinder bore. The upper end of the cylinder bore is threaded to receive a cap 18 centrally bored to form a cylindrical air chamber 19 which is in axial alignment with the cylinder bore and which has a closed upper end drilled and threaded to receive a standard fitting 21. If desired, both cylinders could be embodied in a single casting. Provided in the cylinder bore 14 is a water piston 22 having a recess 23 in its bottom surface which serves as centering means for a coil spring 24 interposed between the lower end of the well 17 and the piston so as to forcibly urge the latter upwardly in the bore 14. The piston 22, it will be noted in Figures 1 and 2, is slightly smaller in diameter than the bore in which it moves so as to provide around the piston a peripheral gap 26 which should be of sufficient width to permit liquid to bleed past the piston. Actual practice has shown that the gap has a direct bearing on the operational characteristics of the charger and depends in considerable measure on the size of the piston, the required velocity of flow, inherent friction in the moving parts, and other factors. However, under ordinary conditions the gap may range between five and ten thousandths of an inch which will produce satisfactory results in operation. It will be seen that the peripheral gap between the piston 22 and the bore 14 in which the former operates is of such size that a deliberate, controlled leakage of water past the piston may occur. Secured to the piston 22, as an integral part thereof or otherwise, is a rod 27 extending concentrically upwardly into the air chamber 19 and having a shouldered and threaded extension 28 at its upper end which carries an air piston comprising a pair of washers 29 and 31 between which is secured a cup leather 32 whose peripheral flange engages the air chamber side wall. The washer 31 serves as a securing nut for the cup leather, being in threaded engagement with the threaded extension 28. The type of mounting shown is purely exemplary as other arrangements may be employed which will suggest themselves to those skilled in the art to which the invention pertains.

Projecting from the side of the tank 6, preferably in vertical planar alignment above the

outlet nipple 7 and located at about three-fifths of the height of the tank, is an air inlet nipple 33 having an internal thread 34 which provides connection to the nipple of the correspondingly threaded stem 36 of a valve housing 37. Provided in the housing 37 is a passage 38 which communicably intersects a larger passage 39 perpendicular thereto and extending completely through the housing. The end of the passage 38 opening 10 within the tank 6 is formed with an enlarged counterbore 41 having a frusto-conical bottom providing a seat 42 for a ball valve 43 which is retained in, although permitted a limited amount of movement axially of, the counterbore by the provision in the latter of a diametrically extending pin 44. The upper end of the passage 39 is tapped to threadedly receive a spring pressed check valve 46 arranged to permit only unidirectional flow of air into the passage from the atmosphere and comprising a standard type of valve similar to a tire valve and housing. The lower end of the passage 39 is also tapped to receive a compression fitting 47 similar to the fitting 21 and both fittings are interconnected by 25 a suitable length of tubing 48 which provides flow communication between the air chamber 19 and the passages 38 and 39.

Referring to Figure 1, the apparatus is shown in its normal condition of repose when no water 30 is being drained from the tank. When an outlet in the service line, or the faucet 10, is opened the resulting flow of water from the outlet nipple 7 into the cylinder bore 14 due to the sudden reduction of pressure on the underside of the piston 22 will cause downward pressure on the piston 22, commensurate with the difference in exposed area between the confronting faces of the air and water pistons, which will cause the latter to descend against the counter pressure of 40 the spring 24 until the water piston reaches its lower limit of travel as indicated in Figure 2, whereupon the water flow may continue directly from the tank into the service line or faucet.

Although the chamber below the piston 22, 45 when the apparatus is in a state of repose as shown in Figure 1, is filled with water which has leaked through the passage 26 during the period of inactivity of the device and which is under the same head of pressure as the water above 50 the piston, the lower chamber pressure will drop instantly to a reduced value as soon as the faucet 10 is opened. Since the upper effective area of the piston 22 is much greater than that of the air piston confronting it, the total downward pressure on the former caused by the water seeking to escape from the tank will be much more than the upward pressure against the air piston. Consequently, the water piston will move downwardly since the only resistance it has to overcome is that of the spring 24, until its lower edge registers with the lowermost point on the periphery of the discharge aperture 49. From this point downwardly, the movement of the piston 55 will be cushioned due to the entrapment of water in the well 17 and the action of the water bleeding upwardly through the gap passage 26. However, due to the fact that the piston 22 has less vertical thickness than the diameter of the aperture 49, when the above-mentioned registry of the piston and aperture occurs, the upper part of the aperture will be uncovered so that water from the tank may flow directly into and through the faucet 10. The pressure on top of the piston 60 22 will be sufficient to continue moving the latter

downwardly until the aperture 49 is substantially completely exposed to admit water from the tank into the faucet or service line with a minimum of impedance.

It will be seen of course that during the downward movement of the water piston 22, the air piston will move correspondingly which will establish a partial vacuum in the conduit 48. At this point, if the water in the tank is above the check valve 42, the water seeking to enter the conduit 48 will close the check valve at the start of the downward stroke of the air piston. As the stroke continues it creates the aforesaid partial vacuum in the conduit 48 drawing atmospheric air through the atmospheric check valve. On the upward stroke of the air piston which is powered by the expanding spring 24 when the valve 10 is closed and as a result of the difference in total pressures on the water and air pistons, respectively, the air drawn into the air cylinder will be forced past the check valve 42 into the tank until sufficient air collects in the tank to force the water level below the check valve and thus replenish the air cushion. However, if the water level is below the check valve, the latter will remain open due to the absence of the weight of water tending to close the check valve. Thus the air in the tank will pass the check 42 and fill the conduit 48 and consequently will fill the air chamber 19. This air will be returned to the tank during the upstroke of the air piston. Thus no additional air is introduced into the tank and the air volume therein is always kept constant.

It will be noted that when the apparatus is in a state of repose, as shown in Figure 1, the well 17 and the portion of the cylinder 14 underlying the water piston 22 will be filled with water. Some of this liquid will escape through the service line or faucet 10 when the latter is opened, but a certain proportion will be trapped under the piston after the bottom surface of the latter passes the lower side of the discharge aperture 49. Ordinarily, if a snug fit existed between the water piston and its cylinder bore, this water would be irrelievably pocketed and would prevent further descent of the water piston to fully uncover the aperture 49. To alleviate this condition, I have developed several methods of relief among which is the provision of the peripheral gap 26 around the water piston, as explained above, which will permit the trapped water to flow upwardly past the piston and eventually out of the discharge aperture. The rate at which the water may escape is of importance, since it is not desirable to unduly retard the descent of the water piston to its full extent and yet it is also not desirable to create a knock which might occur if the piston were allowed to descend forcibly against the abutment 16. Still another feature of advantage connected with the peripheral gap type of water piston is that fine silt which may be contained in the water, and which might accumulate to the point of jamming a tighter piston, will not lodge in the gap, since the repeated forceful water flow therethrough will flush it out.

In Figure 3, I have shown a modified form of water piston 51 designed for snug ring engagement with the cylinder 14 by virtue of a radially expansive piston ring 52 mounted in a peripheral groove 53 formed in the piston. This type of piston could have a greater degree of clearance than the previously described type so as to overcome friction which might be caused by coarse

sand lodging in the peripheral gap surrounding the piston. This type of piston will effect a repeated scraping of the cylinder wall so as to dislodge any accumulations of silt or corrosive elements which may collect thereon so that the water current may carry the foreign matter out through the aperture 49. Venting of the water which may be trapped by such a piston in the well 17, and the portion of the chamber just above the well, may be had through one or more bleeder passages 54 drilled through the piston and also to a certain degree through the gap 56 in the piston ring. Such a design, however, requires that the effective area of the piston be increased slightly in proportion to the resistance of the spring 24 in order to compensate for the slight frictional drag which will be created by the piston ring.

In Figure 4 I have shown another method of relieving the trapped water. In this modification, the piston 57 may be made comparatively snug, although freely slideable, in the bore 14. The piston is provided with a central aperture 58, having a flared bottom portion 59, and with a plurality of radially disposed ports 61 which are drilled completely through and parallel to the axis of the piston and open into the well throat. An annular groove 62, circumscribing the group of ports 61 and provided with a threaded outer side 63, is provided in the piston to receive the threaded annular portion 64 of a bell-shaped cage 66 formed on the lower end of the rod 27 and having cutouts 67 which divide the cage into a plurality of arms 68 forming retainers for a valve disk 69, of rubber or other suitable material, which functions as a valve normally adapted to overlie and close the upper ends of the aperture 58 and the ports 61. The lower end of the well portion of the housing is tapped to receive the threaded portion 71 of a trip rod 72 which extends upwardly into and in axial coincidence with the cylinder 14. In this arrangement, when the water piston 57 descends, under the force of the flowing water, the rod 72 will enter the aperture 58 and will engage the valve 69, as shown in Figure 4, thus opening the ports 61 and permitting the water flowing from the tank through the passage 12 to flow downwardly through the ports and to be discharged through the outlet passage 49.

I claim:

1. In combination with a water supply tank, an air charger having an air chamber in communication with the atmosphere and with said tank, means in said air chamber operative by flow of water from said tank for drawing air into said air chamber, and means associated with said air drawing means operative upon cessation of said water flow for forcing the air in the air chamber into said water supply tank.
2. In combination with a water supply tank, an air charger having an air chamber and a water cylinder associated therewith through which water drawn from the storage tank may flow, means in the water cylinder and responsive to flow of water therethrough for drawing air into said air chamber, and means operative upon cessation of water flow through said water cylinder and associated with said flow responsive means for forcing air within the air chamber into said supply tank.
3. In combination with a water supply tank having an outlet adjacent the bottom thereof

and an inlet adjacent the top thereof, an air charger connected with said outlet and having therein a water cylinder, through which water may flow from the outlet, and an axially aligned air chamber, spaced interconnected pistons in said water cylinder and air chamber and movable axially thereof, one of said pistons being movable by the flow of water passing through said water cylinder and the other piston being correspondingly movable in said air chamber to draw air thereinto, an air line connected with said air chamber, means associated with said pistons and operative upon cessation of flow through said water cylinder to force the air in the air chamber into said air line, and means for connecting said air line to receive air from the atmosphere and to discharge air into said tank inlet.

4. In combination with a water supply tank having an outlet adjacent the bottom thereof and an inlet adjacent the top thereof, an air charger comprising a housing having therein an air chamber and an associated water cylinder, said housing being connected with said outlet and said water cylinder being in flow relationship with said outlet, a service line having a passage entering said water cylinder, a valve housing connected in said tank inlet and provided with intersecting passages, a first of said passages being in communication through a check valve with said tank and a second of said passages being in communication through an atmospheric check valve with the atmosphere, an air line connecting said air chamber and said second valve housing passage, means in said water cylinder and air chamber movable in accordance with water flow from said outlet into said service line for drawing air through said atmospheric check valve and said air line into said air chamber, and means connected with said movable means and operable upon cessation of water flow for forcing the air in the air chamber through the air line, the first of said valve housing passages, and the check valve therein, into said tank through the inlet thereof.

5. In combination with a water supply tank having an outlet adjacent the bottom thereof and an inlet adjacent the top thereof, an air charger comprising a housing having therein an air chamber and an associated water cylinder, said housing connected with said outlet and said water cylinder being in flow relationship with said outlet, a service line having a passage entering said water cylinder, a valve housing connected in said tank inlet and provided with intersecting passages, a first of said passages being in communication through a check valve with said tank and a second of said passages being in communication through an atmospheric check valve with the atmosphere, an air line connecting said air chamber and said second valve housing passage, interconnected water and air pistons respectively in and movable along said water cylinder and air chamber, said water piston being movable in the water cylinder in accordance with the flow of water through the cylinder between said tank outlet and the service line, said water piston during its movement correspondingly moving said air piston in the air chamber to draw into the chamber atmospheric air through said atmospheric check valve and said air line, and means operable upon cessation of water flow for forcing said air in the air chamber through the air line, the first of said valve passages and

the check valve therein, into said tank through the inlet thereof.

6. In combination with a water supply tank having an outlet adjacent the bottom thereof and an inlet adjacent the top thereof, an air charger comprising a housing having therein an air chamber and an associated water cylinder, said housing connected with said outlet and said water cylinder being in flow relationship with said outlet, a service line having a passage entering said water cylinder, a valve housing connected in said tank inlet and provided with intersecting passages, a first of said passages being in communication through a check valve with said tank and a second of said passages being in communication through an atmospheric check valve with the atmosphere, an air line connecting said air chamber and said second valve housing passage, interconnected water and air pistons respectively in and movable along said water cylinder and air chamber, said water piston being movable in the water cylinder in accordance with the flow of water through the cylinder between said tank outlet and the service line, said water piston during its movement correspondingly moving said air piston in the air chamber to draw into the chamber atmospheric air through said atmospheric check valve and said air line, and a spring interposed between said water piston and said air charger housing for moving said pistons upon cessation of water flow so as to force the air in the air chamber through the air line, the first of said valve passages and the check valve therein, into said tank through the inlet thereof.

7. In combination with a water supply tank having an outlet adjacent the bottom thereof and an inlet adjacent the top thereof, an air charger comprising a housing having therein a water cylinder, provided with a continuing well bordered by an abutment forming the lower end of the cylinder, and an axially aligned air chamber, said housing being connected with said outlet and said water cylinder being in flow relationship with said outlet, a service line having a passage entering said water cylinder above the said abutment thereof, a valve housing connected in said tank inlet and provided with a vertical passage extending therethrough and a horizontal passage intersecting said vertical passage and entering said tank, a first check valve in said horizontal passage for confining flow of fluid in the passage unidirectionally into the tank, a second check valve in the vertical passage for confining flow of fluid unidirectionally from the atmosphere into said vertical passage, an air line connecting said vertical passage and said air chamber, interconnected water and air pistons respectively in and movable axially of said water cylinder and air chamber, said pistons being movable in accordance with water flow through the water cylinder from the tank outlet to said service line passage, said movement being limited by engagement of the water piston with said abutment bordering the well and said air piston drawing air through said vertical passage check valve and said air line into said air chamber, means connected with said water piston and operative upon cessation of water flow for moving said pistons to force the air in the air chamber through the air line, the horizontal passage and the check valve associated therewith into said tank, and means operative when said water

piston is in engagement with said abutment for preventing said well.

8. In combination with a water supply tank having an outlet adjacent the bottom thereof and an inlet adjacent the top thereof, an air charger comprising a housing having therein a water cylinder, provided with a continuing well bordered by an abutment forming the lower end of the cylinder, and an axially aligned air chamber, said housing being connected with said outlet and said water cylinder being in flow relationship with said outlet, a service line having a passage entering said water cylinder above the said abutment thereof, a valve housing connected in said tank inlet and provided with a vertical passage extending therethrough and a horizontal passage intersecting said vertical passage and entering said tank, a first check valve in said horizontal passage for confining flow of fluid in the passage unidirectionally into the tank, a second check valve in the vertical passage for confining flow of fluid unidirectionally from the atmosphere into said vertical passage, an air line connecting said vertical passage and said air chamber, interconnected water and air pistons respectively in and movable axially of said water cylinder and air chamber, said pistons being movable in accordance with water flow through the water cylinder from the tank outlet to said service line passage, said movement being limited by engagement of the water piston with said abutment bordering the well and said air piston drawing air through said vertical passage check valve and said air line into said air chamber, means connected with said water piston and operative upon cessation of water flow for moving said piston to force the air in the air chamber through the air line, the horizontal passage and the check valve associated therewith into said tank, and said water piston having a gap extending peripherally around and between the piston and the water cylinder through which water may flow from the well into said service line passage as said water piston approaches said abutment.

9. In combination with a water supply tank having an outlet adjacent the bottom thereof and an inlet adjacent the top thereof, an air charger comprising a housing having therein a water cylinder, provided with a continuing well bordered by an abutment forming the lower end of the cylinder, and an axially aligned air chamber, said housing being connected with said outlet and said water cylinder being in flow relationship with said outlet, a service line having a passage entering said water cylinder above the said abutment thereof, a valve housing connected in said tank inlet and provided with a vertical passage extending therethrough and a horizontal passage intersecting said vertical passage and entering said tank, a first check valve in said horizontal passage for confining flow of fluid in the passage unidirectionally into the tank, a second check valve in the vertical passage for confining flow of fluid unidirectionally from the atmosphere into said vertical passage, an air line connecting said vertical passage and said air chamber, interconnected water and air pistons respectively in and movable axially of said water cylinder and air chamber, said pistons being movable in accordance with water flow through the water cylinder from the tank outlet to said service line passage, said movement being limited by engagement of the water piston with said abutment bordering the well and said air piston drawing air

through said vertical passage check valve and said air line into said air chamber, means connected with said water piston and operative upon cessation of water flow for moving said piston to force the air in the air chamber through the air line, the horizontal passage and the check valve associated therewith into said tank, and said water piston having therein an aperture through which water may flow from the well into said service line passage as said water piston approaches said abutment.

10. In combination with a water supply tank having an outlet adjacent the bottom thereof and an inlet adjacent the top thereof, an air charger comprising a housing having therein a water cylinder, provided with a continuing well bordered by an abutment forming the lower end of the cylinder, and an axially aligned air chamber, said housing being connected with said outlet and said water cylinder being in flow relationship with said outlet, a service line having a passage entering said water cylinder above the said abutment thereof, a valve housing connected in said tank inlet and provided with a vertical passage extending therethrough and a horizontal passage intersecting said vertical passage and entering said tank, a first check valve in said horizontal passage for confining flow of fluid in the passage unidirectionally into the tank, a second check valve in the vertical passage for confining flow of fluid unidirectionally from the atmosphere into said vertical passage, an air line connecting said vertical passage and said air chamber, interconnected water and air pistons respectively in and movable axially of said water cylinder and air chamber, said pistons being movable in accordance with water flow through the water cylinder from the tank outlet to said service line passage, said movement being limited by engagement of the water piston with said abutment bordering the well and said air piston drawing air through said vertical passage check valve and said air line into said air chamber, means connected with said water piston and operative upon cessation of water flow for moving said piston to force the air in the air chamber through the air line, the horizontal passage and the check valve associated therewith into said tank, said water piston having therein ports through which water may flow from the tank into said service line as said water piston approaches said abutment, a valve normally closing said ports, and means engageable with said valve during movement of the water piston for opening said valve.

11. In combination with a water supply tank having an outlet adjacent the bottom thereof and an inlet adjacent the top thereof, an air charger comprising a housing having therein a water cylinder, provided with a continuing well bordered by an abutment forming the lower end of the cylinder, and an axially aligned air chamber, said housing being connected with said outlet and said water cylinder being in flow relationship with said outlet, a service line having a passage entering said water cylinder above the said abutment thereof, a valve housing connected in said tank inlet and provided with a vertical passage extending therethrough and a horizontal passage intersecting said vertical passage and entering said tank, a first check valve in said horizontal passage for confining flow of fluid in the passage unidirectionally into the tank, a second check valve in the vertical passage for confining flow of fluid unidirectionally from the atmosphere into said vertical passage, an air line connecting

connecting said vertical passage and said air chamber, interconnected water and air pistons respectively in and movable axially of said water cylinder and air chamber, said pistons being movable in accordance with water flow through the water cylinder from the tank outlet to said service line passage, said movement being limited by engagement of the water piston with said abutment bordering the well and said air piston drawing air through said vertical passage check valve and said air line into said air chamber, means connected with said water piston and operative upon cessation of water flow for moving said piston to force the air in the air chamber through the air line, the horizontal passage and the check valve associated therewith into said tank, said water piston having therein ports through which water may flow from the tank into said service line as said water piston approaches said abutment, and said piston further having

therein an annular groove provided with screw threads and encircling said ports, a cage threadedly engaged in said annular groove, a disk valve in said cage, and normally overlying and closing said ports, and a rod carried by said housing and extending through said water piston for engaging and raising the disk valve from its position overlying the ports as said water piston approaches said abutment.
